(57) **CLAIM**

The ornamental design for a motor vehicle wheel front face, as shown and described.

DESCRIPTION

FIG. 1 is a front perspective view of a motor vehicle wheel front face showing my new design; and,
FIG. 2 is a front elevational view of the wheel shown in FIG. 1.

The phantom line showing of environment is for illustrative purposes only and forms no part of the claimed design.

1 Claim, 2 Drawing Sheets

FIG. 1

FIG. 2
